(57) **CLAIM**

The ornamental design for a computer harness, as shown and described.

DESCRIPTION

FIG. 1 is a top, rear, right perspective view of a computer harness in accordance with our new design; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; FIG. 7 is a bottom plan view thereof; FIG. 8 is a front elevational view thereof, with the straps in an open configuration; FIG. 9 is an enlarged detail view of a portion of FIG. 5; FIG. 10 is an enlarged detail view of a portion of FIG. 4; and, FIG. 11 is an enlarged detail view of a portion of FIG. 6. The dash-dash broken lines represent portions of the computer harness and form no part of the claimed design.

1 Claim, 11 Drawing Sheets
